UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEATING DEVICE

Application filed March 25, 1927. Serial No. 178,486.

My invention relates to heating devices and has among its other objects the production of devices of the kind described that may be pieces of furniture.

My invention relates broadly to heating devices and particularly to improved heating devices which are built in pieces of furniture in such manner that the furniture may be used in the manner originally intended, this use not being materially affected by the incorporation of heating devices therein.

A particular object of the invention is to conceal improved heating apparatus in a dwelling house, or the like, in such manner that the efficiency of the apparatus is not impaired, nor is the appearance of the room detracted from to any appreciable extent.

Many other objects and advantages of the construction herein shown will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a front elevation of apparatus embodying the invention;

Fig. 2 is a section taken on line 2—2 of Fig. 1;

Fig. 3 is a section taken on line 3—3 of Fig. 1;

Fig. 4 is a section taken on line 4—4 of Fig. 1.

Briefly, the radiator 10 comprises spaced tanks 11 and 12 which communicate with each other through a plurality of tubes 14, the tubes being provided with a plurality of fins 15. The tanks 11 and 12 are connected by pipe fittings 18 and 19, respectively, to any suitable apparatus (not shown) for supplying heated fluid to the radiator, the construction being such that the heated fluid may enter the radiator by way of the pipe fittings 18 and pass from the radiator by way of the pipe fittings 19. Obviously, when the heated fluid passes through the tubes 14,

there will be an exchange of heat between the contents of the tubes and the surrounding atmosphere.

As best shown in Figs. 2, 3 and 4, the radiator 10 is preferably positioned adjacent a wall 20, or the equivalent, the wall 20 being assumed to be one of the walls of a room. Associated with the radiator 10 is a chair which is preferably secured against displacement relative to the wall 20 and is designated generally by the reference character 22. The chair 22 may be of any suitable construction but is preferably provided with a back 23 which is arranged adjacent the wall 20. A substantially vertical passage 24 is provided in the wall which extends from the radiator 10 beyond the upper end of the back 23. As shown, the radiator 10 is positioned beneath the seat of the chair, the seat being identified by the reference character 26. In the illustrated embodiment of the invention, the chair 22 comprises front legs 27 and rear legs 28. Arranged between the legs 27 and extending from the seat 26 to a point spaced from the floor of the room is a plate 29, or the equivalent, and extending between the legs 27 and 28 and extending from the seat 26 to a point spaced from the floor of the room are plates 30, or the equivalent, the arrangement being such that air may enter the space beneath the chair and pass upward through the radiator 10 into the passage 24 and thence back into the room. Of course, it is readily understood that when heated fluid is supplied to the radiator 10, the air of the room will circulate through the radiator 10 and the passage 24 in the manner set forth. The flow of air through the passage 24 is preferably controlled by a damper 32.

The radiator 10 can be positioned in any desired manner underneath the seat 22, but I preferably position it in the manner illustrated in Fig. 2 so that heated air flowing upward from the radiator will not come in contact with the seat 22. For this reason, I preferably provide a baffle plate 36 which forms a continuation of the back 23 and insures that the heated air will not come into contact with the seat.

Obviously, the above described heating ap-

paratus is particularly adapted to be employed in hall-ways, or the like, although it may be employed in other rooms if it is so desired. The apparatus comprises a piece of furniture which serves as a chair but also functions as a heating device. The appearance of the room is not detracted from by any radiator as it is concealed within the chair.

The radiator includes tanks 11 and 12 and a plurality of tubes 14. Pipe fittings 18 and 19 are preferably provided for connecting the radiator to a boiler (not shown), or the equivalent, and the radiator is preferably positioned so that it projects into a passage 24 formed in the wall which is assumed to be one of the walls of a room. As best shown in Fig. 2, the passage 24 extends from the floor of the room to an opening 37 provided in the wall, the upper end of the passage being preferably closed by a plate 38, which, in this instance, is formed integral with a wall 39 forming part of the passage 24. The lining 40 is preferably formed in such manner that it constitutes the inner surface of the passage and protects the wall from the heat of the radiator 10. If desired, a grille 41 may be positioned in the opening 37 and the opening may be concealed behind a picture or other ornament 42.

30 The operation of the apparatus shown, is substantially as follows: Assuming that heated fluid is being circulated through the radiator 10, it is obvious that a current of air will enter the chair below the panels or plates 29 and 30 and will then pass upward through the radiator 10 and the passage 24 and through the opening 37 into the room.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In combination with a wall of a room having a pair of vertically spaced apertures therein and a substantially vertical passage connecting said apertures, a heating unit projecting through the lower of said apertures and extending into said passage, and means connected to said wall and projecting outwardly therefrom into said room so as to conceal said heating unit, said means having an opening therein for the passage of air.

2. In combination with a wall of a room having a pair of vertically spaced apertures therein and a substantially vertical passage connecting said apertures, a heating unit comprising a pair of spaced tanks and horizontally disposed tubular members connecting said tanks, said heating unit projecting through the lower of said apertures and ex-

tending into said passage, and means connected to said wall and projecting outwardly therefrom into said room so as to conceal said heating unit, said means having an opening therein for the passage of air.

3. In combination with a wall of a room having a pair of vertically spaced apertures therein and a substantially vertical passage connecting said apertures, a heating unit, said heating unit projecting through the lower of said apertures and extending into said passage, an element forming part of said passage extending over the heating unit, means connected to said wall and projecting outwardly therefrom into said room so as to conceal said heating unit, said element and means having communicating openings for the passage of air, and means for directing air out of said passage through the upper of said apertures.

4. In combination with a wall of a room having a pair of vertical spaced apertures and a substantially vertical passage connecting said apertures, a heating unit projecting through the lower of said apertures and extending into said passage, a member extending outwardly from the upper edge of the opening above the heating unit, a member providing a piece of furniture for concealing said first mentioned member, said members being arranged relatively to the floor of the room to provide for the passage of air through said heater unit and to allow the introduction and removal of the heater unit from said passage.

5. In combination with a wall of a room having a pair of vertically spaced apertures therein and a substantially vertical passage connecting said apertures, a heating unit projecting through the lower of said apertures and extending into said passage, a plurality of means connected to said wall and projecting outwardly therefrom into said room, one of said means providing part of said passage and means to conceal said heating unit, said plurality of means having communicating openings for the passage of air, and said heating unit being located in the opening of one of said means, the other of said means providing a piece of furniture.

In testimony whereof, I have hereunto signed my name.

ARTHUR B. MODINE.
